US00D861727S

(12) **United States Design Patent** (10) Patent No.: **US D861,727 S**
 Niven et al. (45) Date of Patent: ** *Oct. 1, 2019

(54) **DISPLAY SCREEN OR PORTION THEREOF WITH ICON**

(71) Applicant: **Dyson Technology Limited**, Wiltshire (GB)

(72) Inventors: **Ruth Niven**, Bristol (GB); **Leanne Joyce Garner**, Bristol (GB); **Andrew James Holden**, Cheltenham (GB); **Adam James Bates**, Oxford (GB)

(73) Assignee: **Dyson Technology Limited**, Malmesbury, Wiltshire (GB)

(*) Notice: This patent is subject to a terminal disclaimer.

(**) Term: **15 Years**

(21) Appl. No.: **29/648,612**

(22) Filed: **May 22, 2018**

(30) **Foreign Application Priority Data**

Nov. 24, 2017 (EM) 004521524-0020

(51) **LOC (12) Cl.** **14-04**

(52) **U.S. Cl.**

USPC **D14/492**; D14/491

(57) **CLAIM**

We claim the ornamental design for a display screen or portion thereof with icon, as shown and described.

DESCRIPTION

The single FIGURE is a front view of a display screen or portion thereof with icon showing our new design.

The broken-line perimeter illustrates a display screen or portion thereof and forms no part of the claimed design.

1 Claim, 1 Drawing Sheet
